TOY

Edward Spritzer, Bronx, N. Y.

Application July 31, 1937, Serial No. 156,636

3 Claims. (Cl. 46—51)

The invention relates to a toy comprising a handle member to which a rope is attached in such a manner that its two ends project from the end thereof. It is well known that children find great pleasure in playing with ropes and in performing all kinds of tricks by swinging, and otherwise manipulating, such ropes.

The main object of the present toy is to provide a device, such as described, with which a great many feats of skill may be performed. Another object is to provide a toy of the type in which the rope may be used as a single rope or as a double rope, of either equal or unequal lengths. A still further object is to provide simple means for securing and changing the rope. Additional objects are to make a toy of the class described which is neat in appearance, which is sturdy and not easily broken, which when not in use can be stored away so as to occupy but small space, and which can be manufactured and sold at a relatively low price.

These and various other objects and advantages will be readily understood from the following description and from the accompanying drawing of preferred embodiments of the invention, in which, however, modifications might be made without departing from the scope of the appended claims. In the drawing:

Fig. 1 is a front elevation of the toy, shown partly in cross-section;

Fig. 2 is a similar front elevation but shown with the ends of the ropes being spun or manipulated by the operator;

Fig. 3 is another front elevation, shown with the ends of the rope wound around the handle member;

Fig. 4 is a top view; and

Fig. 5 is a top view of a slightly modified device.

Referring now to Figs. 1 to 4 inclusive, the toy consists of a handle member 10 provided with an enlarged head 11 through which two holes 12 and 13 are drilled, as plainly shown. A hole 14 is also drilled transversely through the handle member immediately below the head. The upper ends of the holes 13 and 14 are preferably bell-mouthed. A rope 15 is threaded through the holes in the head of the handle member, as plainly shown, and the ends of this rope may be provided with light weights 16 and 17, or the ends of the rope may merely be knotted.

It will be seen that if the handle member 10 is grasped in the hand, so the toy is held either horizontally or vertically, that the ends of the rope may be rotated, as shown in Fig. 2, so as to, for example, wind themselves around one another and, when turned in the other direction, unwind. Similarly other tricks may be performed. It will also be noted that while the friction of the ropes in the various holes will hold the rope in

whatever position it is placed in, the rope may readily be drawn completely through to one end, so that, for example, the ball 16 will engage in the hole 12. Thus one single rope is obtained with which various tricks may be performed.

In like manner the ends of the rope may be made of uneven length to perform still other tricks. When the toy is not in use the rope may be wound on the handle member, as plainly shown in Fig. 3. The toy may also be provided with a base member 18 on which it may be made to stand.

While I prefer to make the toy of round cross-section, as shown in Fig. 4, it is evident that it might also be made of a flat piece of material, as shown at 19, in Fig. 5; particularly when it is desired to produce a toy of this kind at very low cost.

Having described the invention and its objects, what I claim as new and wish to protect by Letters Patent is:

1. A toy of the class described comprising a handle member, an enlarged head formed at one end of the handle member, two spaced holes drilled in the head parallel with the axis of the toy and on opposite sides of and outside the handle, a transverse hole drilled through the handle member near the head, and a rope threaded through said holes in such a manner that the ends of the rope will extend outside of the said head.

2. A toy of the class described comprising a handle member, an enlarged head formed at one end of the handle member and having a substantially flat top, two spaced holes drilled in the head parallel with the axis of the head and outside the handle member and forming right-angles with the top of the head, a transverse hole drilled through the handle member adjacent the head, a rope threaded through said holes in such a manner that the ends of the rope will extend outside of the said head, and the sizes of the rope and holes so proportioned that the rope will be frictionally held in the holes in whatever position placed.

3. A toy of the class described comprising a handle member, an enlarged head formed at one end of the handle member and having a substantially flat top, two spaced holes drilled in the head parallel with and equidistant from the axis of the toy and outside the handle member and forming right-angles with the top of the head, a transverse hole drilled through the handle member adjacent the head, a rope threaded through said holes in such a manner that the ends of the rope will extend outside of the said head, and the rope adjustable in said holes so that the lengths of each end of the rope may be varied as desired.

EDWARD SPRITZER. 60
